UNITED STATES PATENT OFFICE.

JAKOB SCHÄRER-NUSSBAUMER, OF ERLENBACH, NEAR ZÜRICH, SWITZERLAND.

WINDING-MACHINE.

1,033,622.

Specification of Letters Patent. Patented July 23, 1912.

Application filed June 15, 1910. Serial No. 567,021.

To all whom it may concern:

Be it known that I, JAKOB SCHÄRER-NUSSBAUMER, a citizen of the Republic of Switzerland, residing at Erlenbach, near 5 Zürich, Switzerland, have invented certain new and useful Improvements in Winding-Machines; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

Attempts have already been made to run winding-machines for cops or bobbins at a higher speed, for the purpose of reducing the time necessary for filling a bobbin; the 20 results, however, have not proved satisfactory, as the centrifugal-force is found to act disadvantageously upon the rotary parts of the winding-mechanism, such, for instance, as the thread-guide.

In order to enable more rapid winding, without the velocity of the revolving parts being increased, both the spindle and the thread guides are rotated. At the same time there takes place a to and fro axial movement of the spindle and the thread guides in relation to each other. Both the spindle and the thread guides are positively geared together and at the same time positively displaced axially with relation to each other 35 by one and the same system of driving mechanism.

Since the time during which the thread travels from the lower part of the conical bobbin-end to the upper part thereof, is 40 much shorter than hitherto, it is requisite that the compensation of the thread be more accurate and quick than in prior machines, and for this purpose I provide a special compensating-device for each spindle.

My invention is illustrated in the accompanying drawings, which show one form of construction, in which several threads are wound with counter-rotation.

Figure 1 is a front elevation of a part of 50 the machine. Fig. 2 is a cross-sectional view. Fig. 3 is a vertical sectional view showing a bobbin-spindle and contiguous parts, drawn to a larger scale. Fig. 4 shows diagrammatically the conical bobbin-end as hitherto wound. Fig. 5 is a like view show-

ing the bobbin-end as wound according to this invention. Fig. 6 is a section on the line A—B of Fig. 2, drawn to a larger scale. Fig. 7 is a section on the line C—D of Fig. 2.

1 designates the main-shaft, from which the shaft 2 is driven. On the latter there is mounted for each cop or bobbin-spindle a friction-disk 3, engaging with a second friction-disk 4. To the latter there is rigidly connected a toothed sleeve 5, with which there meshes a gear 6, which is rigidly connected with a second gear 7, that meshes with a further gear 8. On the shaft 9 of the gear 8 there is fixed a cam 10, the two halves of which, as presented by a vertical axial section, are symmetrical, so that the ascending cam-track is symmetrical to the descending one. This cam 10 presents a groove 11, into which there projects a pin 12, which is connected with the axially sliding bobbin-spindle 13, that passes loosely through the toothed sleeve 5. The cam 10 is furnished on the tip edge with teeth 14, which mesh with a toothed sleeve 15, rigidly secured to the spindle 13. The sleeve 5 is mounted with capability of turning on a sleeve 17 fixed to an arm 16. On the friction-disk 4 two rods 18 are secured, which support the thread-guide 19 in well-known manner.

When the disk 3 rotates, the disk 4, and thus the thread-guide 19, will be revolved; at the same time, however, through the transmission-mechanism 5, 6, 7, 8, the cam 10, and by means of the teeth 14 the sleeve 15 and spindle 13, will be rotated. Simultaneously, by means of the cam groove 11 and pin 12, the spindle 13 will be reciprocated up and down. The rotary motion of the spindle, its axial motion, and the revolving motion of the thread-guide are thus all in positive connection.

With the cam 10 there is rigidly connected a cam-disk 20. Against the latter there bears a roller 21, mounted on a lever 22, which is secured to a bent rod 23, that has its bearing in a block 24 (Fig. 1). The other end of the rod 23 (Figs. 2 and 7) bears against a roller 25 of a lever 26, which turns in a bearing 27 and carries the thread-guide 29 of the compensating-device thus constituted. A spring 28 has the tendency to keep the roller 25 always pressed against the lever 23, and thus cause the roller 21 to

bear against the cam-disk 20. As is seen from Fig. 1, each spindle is provided with a compensating-device such as described.

In prior cop-winding-frames, only a small 5 rotative movement of the spindles and the thread guides in relation to each other could take place, since there was no positive connection of the means gearing both parts. Thus on axial motion of a part of the spindle, or of the thread-guide, during each lift 10 of this part, a portion of the thread has been wound on, as indicated by the line $x-y$, Fig. 4, so that during this lift, two turns of thread have been wound on. According to 15 this invention, a more rapid winding is effected in consequence of the positive connection of the impelling means for both the spindle and the thread-guides, so that a portion of the thread will be wound onto the 20 cone, as shown by line $z-w$, Fig. 5, at each axial lift of this part, that is to say, in the same time as with the prior bobbin. This piece of thread $w-z$ lies, in the case illustrated, in five turns on the cone. According 25 to my invention, therefore, more thread can be wound on in the same time than hitherto; that is to say, the bobbin can be filled in a shorter time.

It is obvious that the motion of a thread 30 guide of definite length, for the purpose of filling the cone, takes place within a shorter time than hitherto. There is therefore less time for the compensation by the compensating-device than has previously been the 35 case, where a single compensating-contrivance has been employed for all the spindles of a machine. The compensating-device must, therefore, be more sensitive and must operate more quickly; and this is the reason 40 why, according to the present invention, each spindle is furnished with its own compensating-device, as shown in Fig. 1.

Having now particularly described and 45 ascertained the nature of the said invention and in what manner the same is to be performed, I declare that what I claim is:

1. In a winding machine, a bobbin spindle, a thread guide, means for rotating the

spindle, means for rotating the thread guide, 50 means operating simultaneously therewith for positively moving the spindle and the thread guide to and fro axially in relation to each other, and means for positively connecting the rotating and moving means to each other, substantially as described. 55

2. In a winding machine, a plurality of bobbin spindles and thread guides, separate means for rotating each spindle, separate means for rotating each thread guide, separate means operating simultaneously therewith for positively moving each spindle and the corresponding thread guide to and fro axially in relation to each other, means for 60 always positively connecting the rotating and moving means of each spindle and the corresponding thread guide in relation to each other, and a separate thread compensating device provided for each spindle, substantially as described. 65

3. In a winding machine, a bobbin-spindle, a thread guide, a cam drum forming a toothed wheel, and of symmetrical halves, 70 said drum positively rotating and at the same time axially displacing said spindle, and toothed wheels connecting said cam 75 drum to said thread guide.

4. In a winding machine, a plurality of bobbin spindles and thread guides, a cam drum provided for each spindle forming a toothed wheel and of symmetrical halves, 80 said drum positively rotating and at the same time axially displacing said spindle, toothed wheels connecting said drum to the corresponding thread guide, a thread compensating device for each spindle, and a cam disk secured to said cam drum and actuating said compensating device, substantially as described. 85

In testimony that I claim the foregoing as my invention, I have signed my name in 90 presence of two subscribing witnesses.

JAKOB SCHAERER-NUSSBAUMER.
